FLOWER POT AND OVERFLOW DISH

Marten Gottsagen, 1212 Lake Shore Drive,
Chicago, Ill. 61610

Filed May 16, 1975, Ser. No. 578,001

Term of patent 14 years

Int. Cl. D11—02

U.S. Cl. D11—156

Fig. 1

Fig. 2

Fig. 3

Fig. 4

Fig. 5

Fig. 6

Fig. 7

Fig. 8

FIG. 1 is a perspective view of a flower pot with water overflow dish showing my new design;

FIG. 2 is an exploded perspective view of a flower pot and water overflow dish showing my new design;

FIG. 3 is a front elevational view thereof;

FIG. 4 is a side elevational view thereof;

FIG. 5 is a top plan view thereof;

FIG. 6 is a bottom elevational view of the water overflow dish showing my new design;

FIG. 7 is a bottom plan view of the flower pot showing my new design; and

FIG. 8 is a top plan view of the water overflow dish showing my new design.

I claim:

The ornamental design for a flower pot and overflow dish, as shown and described.
